PLACER MINING MACHINE

James W. White, Los Angeles, Calif.

Application March 25, 1946, Serial No. 656,937

4 Claims. (Cl. 209—471)

1

This invention relates to a placer mining machine, and it is an object of this invention to provide a machine so constructed that dirt and gravel containing gold and other minerals may be passed through the machine and the mineral separated from the dirt and gravel and retained in the machine while the dirt and gravel are carried from the machine.

Another object of the invention is to provide a placer mining machine wherein the dirt and gravel are fed from a hopper onto a reciprocating table under harrows or agitators mounted at opposite sides of the hopper so that during reciprocating movement of the table the harrows will move through the dirt and gravel and the dirt and gravel so acted upon the harrow will gravitate to the bottom of troughs on the table provided for this purpose.

Still another object of this invention is to provide a placer mining machine wherein an endless conveyor is employed for delivering the gold laden dirt and gravel to the hopper and another endless conveyor employed for receiving the dirt and gravel after the gold has been separated therefrom and depositing the dirt and gravel upon a dump, or into vehicles for conveying it to a suitable place of disposal.

Yet another object of this invention is to so construct a placer mining machine that a large quantity of gold bearing dirt and gravel may be handled and passed at a relatively high rate of speed along sloping side portions of the table to which it is delivered from the hopper.

A still further object of this invention is to provide the table with gold receiving troughs so mounted that they may be easily slid into and out of place and thus permit the troughs to be removed for emptying gold accumulated therein without disturbing the remainder of the machine.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a side elevation of a placer mining machine constructed according to an embodiment of my invention.

Figure 2 is a vertical section taken on the line 2—2 of Figure 1.

2

Figure 3 is a fragmentary vertical section taken on the line 3—3 of Figure 1.

Figure 4 is a fragmentary top plan view of the riffles,

5 Figure 5 is a vertical section taken on the line 5—5 of Figure 4.

Figure 6 is a fragmentary vertical section of the harrows,

10 Figure 7 is a detail side elevation of the driving pulley, and

Figure 8 is a detail section of the screen of my machine.

Referring to the drawings, the numeral 20 designates generally a supporting frame for supporting a hopper frame 21 and the riffle trough table 22. The frame 20 comprises base members 23 and vertical members 24 fixed together at the base. Spaced from the base and fixed to the upright frame members 24 are horizontal strengthening members 25.

The motive power for this machine is derived from an engine 26 which is mounted on an extension of the base members 23 beyond the vertical members 24. A pulley 27 is mounted by 15 bearings 28 on one of the frame members 24 and is driven from the engine or motor 26 by a belt 29 over a pulley 30 fixed to the drive shaft 31 of the engine 26. The pulley 27 is fixed to the shaft 32 on one side of the supports 24, and the shaft 32 is rotatably supported by the bearing 28 and a vertical support 33 between the uprights 24 and the cross member 25. A sprocket 34 is fixed on the shaft 32. Supported across the top of the frame 20 is another shaft 35 to which is fixed a sprocket 36 which is driven by a chain 37 between the sprockets 34 and 36.

A conveyor belt 38 is driven by the shaft 35 for conveying the dirt and gravel containing gold to the top of the machine. The ore is carried by buckets 39 fixed to the belt 38. The lower end of the belt 38 is carried by a sprocket 40 mounted on a rotatable shaft at the base of the frame.

The ore conveyed to the top of the frame 20 is dropped onto an inclined screen 41. The screen 41 is rockably connected to the frame 20 at its upper end as at 42 and the lower edge is slidably supported on the upper edge of the hopper 43. The larger pieces of gravel and dirt are guided over the screen 41 to the chute 44, hinged to the 45 hopper frame 21 and dropped from there to a waste pile. Any of the dirt and gravel passing through the screen 41 before it reaches the hopper is guided to the hopper 43 by another chute 45, hinged also to the frame 20.

55 The hopper 43 is fixed to a hopper frame 21

which also support a series of harrows or agitators 46 extending downwardly from the hopper 43. The hopper frame 21 is supported in such a manner that it is slideable vertically in the frame 20, and is supported therein by cords or cables 47. The cable 47 is guided over a pulley 48 and outwardly to a crank shaft 49 which may be operated by a hand crank 50, for raising and lowering the hopper frame 21, together with the hopper 43 and harrows 46.

A descending series of riffles 51 are fixed to a carriage or riffle frame 22. The riffle frame 22 is of a generally triangular configuration having a receiving tray 52 fixed to the apex thereof. A series of riffles or troughs 51 are fixed to the vertical sides of the frame 22 in descending arrangement whereby the ore spills from the tray 52 downwardly into and over the riffles 51. The riffles 51 are so formed that each is closed at the end and the lower edges of each riffle overlaps the upper edge of the next lower riffle so that all of the ore will be passed through each riffle successively with no spilling between the riffles or troughs 51.

The carriage 22 is mounted on rollers 53 which roll on a track or rail 54. The rail 54 is securely fixed to the frame 20 so that the carriage 22 may be mounted securely thereon. A pitman 55 is rockably fixed to the carriage 22 by a shaft 56 mounted securely thereon and the other end of the pitman 55 is connected to a crank pin 57 on a disc 58, which disc 58 is fixed to the shaft 32, whereby the carriage is imparted reciprocating motion from the engine 26.

The riffles 51 and tray 52 are longer than the harrows 46 to provide for reciprocating motion of the carriage 22 while the harrows 46 are fixed relative to the frame 20.

Harrow teeth 59 are fixed in pairs to the harrow 46 and depend downwardly into the riffles 51 for agitating the dirt and gravel containing ore. The teeth 59 do not reach the bottom of the riffles 51 but are spaced from the bottom and edges thereof.

The dirt and gravel spilling over the riffles 51 finally spills over the lower edge of the carriage 22 when the gold or desired material has been removed, through a waste hopper or chute 60, and then onto a conveyor belt 61, which is chain driven from the engine 26.

The dirt and gravel is delivered to the waste pile by the conveyor belt 61.

Another conveyor 62, having buckets 63, is supported on the frame 20, and chain driven from the engine 26, for raising the dirt and gravel from the waste pile to a truck or other means for transporting the waste to some other point. The waste from this conveyor 62 is guided from the conveyor by a chute or guide 64, depending from the frame 20.

In order to agitate the dirt and gravel in the riffles air tubes 65 are provided in the bottom of each riffle 51. The tubes 65 are fixed in the riffles 51 and extend through one end wall and are closed or capped off at their end within the riffle 51. The tubes 65 are so positioned that they are spaced slightly above the bottom of the riffles and are provided with openings 66 along the bottom thereof between the tubes 65 and the bottom of the riffles 51. Air under pressure is supplied to the tubes 65 from some external source of compressed air through a flexible tube 66 and a manifold 67 which extends along the end of each side of the carriage 22.

In the use and operation of this machine the

dirt and gravel bearing ore is fed into the hopper 43 by the conveyor 38 which is driven from the engine by the chain 37 and sprockets 34 and 36. The ore then passes over and through the screen 51 into the hopper 43 and onto the tray 52. The carriage bearing riffles 51 is reciprocated by the pitman 55 driven by the engine 26 through the belt 29 and crank 58. The ore then spills into the riffles 51 where it is agitated by the harrow teeth 59 and air in the tubes 65 and into succeeding riffles until only dirt and gravel is deposited on the conveyor 61 to be delivered to the waste pile. The metal in the riffles is gotten by raising the harrow frame 21 so that the harrow teeth 59 are raised from the riffles 51 and the riffles may then be raised out of the riffle frame and carriage 22 and the metal removed.

The waste conveyor 62 is driven also by the engine 26 by the chain 68 and sprockets 69, and a chain 70 connects a sprocket 71 with another sprocket 72 to drive the conveyor 61.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claims.

Having thus described my invention what I claim is:

1. A placer mining machine comprising a supporting frame, a hopper frame vertically slideable in said first frame, means carried by said supporting frame for raising and lowering said hopper frame, agitators fixed to said hopper frame, a carriage reciprocable in said first frame, oppositely disposed descending series of riffles carried by said carriage, means for reciprocating said carriage, said agitators extending into said riffles for agitating the ore, compressed air tubes carried by said riffles having openings formed therein for agitating the ore, a conveyor on said supporting frame for carrying ore to said hopper, a conveyor on said frame for carrying the waste ore from the machine and a conveyor for loading the waste ore to a truck, and an engine mounted on said frame for reciprocating said carriage and for operating said conveyors.

2. In a placer mining machine a hopper, a reciprocable carriage, an ore receiving tray carried by said carriage below said hopper, downwardly and outwardly extending series of riffles removably carried by said carriage on opposite sides of said tray, a harrow frame carried by said hopper, agitators depending from said frame and extending into said riffles for agitating the ore upon reciprocating movement of said carriage, air tubes carried by said riffles for agitating the ore, and means for reciprocating said carriage.

3. A placer mining machine comprising a vertically adjustable hopper frame, a hopper in said frame, a reciprocable carriage, an ore tray fixed to said carriage below said hopper, descending series of riffles removably mounted on said carriage on opposite sides of said tray, agitators fixed to said hopper frame and extending into said riffles for agitating the ore upon reciprocating movement of said carriage, means for conveying ore to said hopper, means for removing the waste from said machine, and means for reciprocating said carriage and operating said ore conveying means.

4. A placer mining machine comprising a ver-

tically adjustable hopper frame, a hopper in said frame, a reciprocable carriage, an ore tray fixed to said carriage below said hopper, descending series of riffles removably mounted on said carriage on opposite sides of said tray, agitators fixed to said hopper frame and extending into said riffles for agitating the ore upon reciprocating movement of said carriage, means for conveying ore to said hopper, means for removing the waste from said machine, means for reciprocating said carriage and operating said ore conveying means, and means removably securing said series of riffles and said tray on said carriage.
